(57) **CLAIM**

The ornamental design for an antenna support structure as shown and described.

DESCRIPTION

1. Antenna support structure

1.1 : Perspective

1.2 : Front

1.3 : Back

1.4 : Top

1.5 : Bottom

1.6 : Left

1.7 : Right

An antenna support structure is disclosed having a first planar member orthogonally coupled to a second planar member where both the first planar member and the second planar member each comprise a plurality of apertures.
